UNITED STATES PATENT OFFICE.

GEORGE FRANCIS CLARK, OF UTICA, NEW YORK.

DESIGN FOR A SPRAYER-BODY.

SPECIFICATION forming part of Design No. 33,500, dated November 6, 1900.

Application filed October 3, 1900. Serial No. 31,936. Term of patent 7 years.

to all whom it may concern:

Be it known that I, GEORGE FRANCIS CLARK, a citizen of the United States, residing at Utica, in the county of Oneida and State of New York, have invented and produced a new and original Design for a Sprayer-Body, of which the following is a specification, reference being had to the accompanying drawings, forming a part hereof.

Figure 1 shows a perspective view of a sprayer-body of my design. Fig. 2 shows a side elevation of the same.

The feature of the design is the form and arrangement of the parts constituting the sprayer-body—that is to say, the lower cylindrical body portion 1, a superposed similar

cylindrical body portion 2, the loop or handle 3, and the small cylinder 4, arranged at one end of the cylinders 1 and 2, substantially as shown.

Having described my invention, what I claim as new, and desire to secure by Letters Patent, is—

The design for a sprayer-body, substantially as herein shown and described.

In witness whereof I have hereunto subscribed my name, in the presence of two witnesses, this 29th day of September, 1900.

GEORGE FRANCIS CLARK.

Witnesses:

E. WILLARD JONES,
S. A. BROWN.
